[57] **CLAIM**

The ornamental design for a transportable combination beach towel and pillow, as shown and described.

DESCRIPTION

FIG. 1 is a perspective view of a transportable combination beach towel and pillow showing our design, taken from the top looking toward the left hand side, with the right hand side thereof being the mirror image of the left hand side shown;

FIG. 2 is a top plan view of our design as shown in FIG. 1;

FIG. 3 is a bottom plan view of our design as shown in FIG. 1;

FIG. 4 is a perspective view of our design in the rolled-up position; and,

FIG. 5 is an enlarged perspective view of a portion of our new design, as shown in FIG. 1, with the pillow pocket closure member partially opened and the pillow partially removed from the pocket.

FIG. 1

FIG. 2

FIG. 3

FIG. 4

FIG. 5
